UNITED STATES PATENT OFFICE.

FERDINAND BUCHHOP, OF NEW YORK, N. Y., ASSIGNEE TO THE MEYROWITZ MANUFACTURING COMPANY, A CORPORATION OF NEW JERSEY.

LENS-GRINDING MACHINE.

938,459.

Specification of Letters Patent.

Patented Nov. 2, 1909.

Application filed July 6, 1908. Serial No. 441,976.

To all whom it may concern:

Be it known that I, FERDINAND BUCHHOP, a citizen of the United States, residing at the city of New York, in the borough of Brooklyn and State of New York, have invented certain new and useful Improvements in Lens-Grinding Machines, of which the following is a full, clear, and exact description.

10 My invention relates to lens grinding machines, and consists particularly in a complete organized machine adapted to grind a number of lenses simultaneously.

It is a particular purpose of my invention to provide means by which lenses of every ordinary character, either spherical or cylindrical or toric, and of any size and focal length, may be ground, and furthermore, by which lenses of one character are 20 ground in one part of the machine at the same time that lenses of another character are being ground in another portion of the machine. A machine of this character is particularly adapted for the use of retail opticians who can in this way make a great variety of lenses very rapidly, turning them out in lots limited only by the capacity of the machine, but in which the individual lenses are of different characters to suit the 25 variety of prescriptions which the optician is called upon to fill.

It is evident that the machine must be adapted to simultaneously grind any proportion of spherical or toric or cylindrical lenses within its capacity. In carrying out my invention, I secure this result by a machine of compact and simple character, in which the adjustments for different kinds of lenses are made very easily, so as to be 35 adapted to the use of any retail optician who is ordinarily not a skilled technical mechanician.

With these and other objects in view, my invention consists in the features of construction and combination as hereinafter set forth and claimed.

In the drawings: Figure 1 is a side elevation of a lens grinding machine embodying the principles of my invention. Fig. 2 is a 50 vertical transverse sectional view of the same. Fig. 3 is a section on the line X-X of Fig. 2, looking in the direction of the arrow III. Fig. 4 is a section on the line X-X of Fig. 2, looking in the direction of the arrow IV. Fig. 5 is a vertical sectional

view of the grinding tool spindle and an attachment which I apply thereto for grinding toric lenses. Fig. 6 is a plan view of the same. Fig. 7 is an enlarged detail sectional view of a lens holding tool.

Referring to the drawings, in which like parts are designated by the same reference sign, 1 indicates the frame of the machine preferably of generally rectangular outline with a flat top or table portion 2 through 65 which the various grinding heads or spindles project. This table also carries work-supporting devices by which the lenses are held against the grinding tools and properly moved or manipulated during the grind- 70 ing action.

I provide a plurality of vertical spindles 3 journaled in bearings 4 forming part of brackets 5 fixed to the frame 1 of the machine. 6 designates shafts also preferably 75 vertically journaled in brackets 7 at the opposite side of the frame 1 from the spindles 3. These shafts constitute the operating means by which the work is moved over the surface of the grinding tool in use. The 80 shafts 6 are driven from the counter-shaft 8 revolving in bearings 9 at the base of the frame 1, and having the usual tight and loose pulleys 10 and 11. This counter-shaft 8 has pulleys 12 from which belts 13 pass 85 over the idlers 14 to pulleys 15 loose on certain of the shafts 6. To each pulley 15 there is rigidly or integrally fixed a grooved pulley 17. The remainder of the spindle driving shafts 6' are provided with correspondingly grooved pulleys 17', also loose thereon. These are belted to the pulleys 17, which are fixed to the pulleys 15. Pulleys 17 and 17' have a part 20' which is coned or hollowed out to form part of the friction 95 clutch.

21 designate cone members of the friction clutches splined on the shafts 6, 6' and spring-impelled downward by the springs 22.

100 23 denote collars forming part of the cone members 21 of the friction clutches and which are engaged by the pins 24 of forked levers 25 which embrace the shafts 6 in the manner particularly shown in Figs. 2 and 105 4. The levers 25 are pivoted on brackets 26 forming part of the frame of the machine, and may be displaced upward by cam arms 27 fixed to rods 28 extending trans- 110 versely through the machine.

29 designates handles or lever arms by which the rods 28 are angularly displaced and the cams 27 caused to raise or lower the levers 25. It is evident that these movements of the levers 25 are accompanied by corresponding movements of the cone clutch members 21, so that the shafts 6, 6' are engaged in or disengaged from driving relation by movements of the operating handles 29. These handles are on the side of the machine having the grinding spindles 3, and which may be termed the front of the machine. Each of the shafts 6, 6' serves a double function in accordance with my present invention. There are fixed on the shafts one or more pulleys 35 which are belted to corresponding pulleys 36 on the spindles 3, by belts 37.

I ordinarily make use of cone pulleys so that the speed ratio can be varied. It is evident that the spindles 3 operate, therefore, in unison with their corresponding driving shafts 6, 6' and are therefore controllable through the lever arms 29 above described. In addition to this function of the shafts 6, 6' I provide means by which the work-supporting devices are moved or manipulated for the respective grinding heads by means of these shafts. 38 designate face plates or crank disks fixed to the upper extremities of the spindle 6, 6' which project through the top of the table 2 for this purpose. As shown in Fig. 2, I make the face plates or crank disks 38 diametrically slotted at 39, so that the crank pins 40 may be adjusted to different radii of throw by tightening the respective adjusting bolt or screw 41.

42 designates a cross-head guided to reciprocate on fixed pins 43 rigidly supported from the frame of the machine at 44. This cross head has a link connection 45 with the crank pin 40, so as to be moved to and fro through an adjustable degree of movement 45 therefrom.

46 designates the work-supporting device which is adjustably fixed to a freely swinging arm 47 pivoted on the cross-head 42. The work-supporting device 46 preferably 50 has a rigid rod 48 which is received in a sleeve 49 on the arm 47 and tightened in any desired relation by a set-screw 50. This arm 47 swings freely in a vertical plane and may be adjusted from side to side by 55 changing the relation of the pivot pins or screws 51, by which the arm 47 is supported on the cross-head 42.

53 designates a rigid projecting pin or member depending downwardly from the work-supporting device 46, and which may be pointed at its lower end 54, so as to engage the usual lens holder or "runner" with a universal joint connection.

55 is a weight resting on the work-supporting device 46, for imparting a proper

bearing engagement of the work on the grinding heads in action.

In grinding spherical lenses, a spherical tool 60 is fastened at the upper extremity of any of the spindles 3, preferably by means of a chuck 61. The work-supporting device 46 is now adjusted so that the pin point 54 reciprocates over the surface of the tool 60 preferably to one side of the center thereof, and through a range of 75 throw suitable to the character of the particular lens to be ground. The lateral adjustment is made by the screw pivot pins 51, and the adjustment of the throw is determined by varying the position of the crank-pin 40 in its slot 39. The lenses, cemented to any usual "runner," are thereupon pressed upon the rotating surface of the tool 60, and given a continuously shifting movement which is suitable for the purposes of grinding spherical lenses in a manner which is well known and need not be particularly described in this application.

The above mechanism is not adapted to grinding cylindrical or toric lenses, and I provide means by which any number of these can be ground on certain of the grinding spindles, while the remaining spindles are in use for spherical lenses.

Referring particularly to Figs. 5 and 6, 65 designates a device adapted to be clamped upon the frame 1, so as to be rigidly supported in a position above the spindle 3 and beneath the corresponding work-supporting device 46. The frame 65 is adapted to constitute a support for a toric lens grinding tool and is adapted to impart a reciprocating movement to such tool during the action of the machine in a direction at right-angles to the reciprocating movement of the work. 105 For this purpose the frame 65 has a pair of parallel guide rods 66 which constitute sliding supports for a cross-head 67 adapted to receive a toric or cylindrical tool 68 in fixed relation thereon. 69 designates a face plate 110 or crank disk similar in construction to the crank disk 38 and having an adjustable crank pin 70 with a connecting rod 71 extending to the cross-head 67, so as to reciprocate the same on its guiding rods. The 115 crank disk 69 is receivable upon the upper extremity of the spindle 3 in place of the tool 60 already described. By this mechanism the toric or cylindrical tool 68 is caused to reciprocate with any desired throw during the back and forth reciprocation of the work. The speed relations are fixed by the cone pulleys 35 and 36, and it is ordinarily advantageous to have the back and forth reciprocation of the toric tool several times 120 as rapid as that of the work, which causes the tracing of very complicated geometrical curves particularly adapted to grinding a perfect toric or cylindrical lens. It will be found that any particular point on the tool 130

passes over the lens in a continuously varying path, which produces a uniformly distributed grinding action at every point.

The method of clamping the frame 65 upon the table 2 may, of course, be of any desired sort. I prefer to make use of brackets 75 which receive screws 76 passing down into nuts 77 on the under side of the table. The shape of the brackets 75 is adapted to 10 fit over the edge of the usual pan 78 which surrounds the grinding head, so as to collect the emery or polishing abradant which escapes from the surface of the tool in the grinding action. During the operation each 15 lens can be separately inspected or removed or readjusted by stopping its appropriate grinding spindle through the corresponding lever arm 29. This action does not interfere with the grinding of the remaining 20 lenses, so that the machine can be kept constantly working at its full capacity, regardless of the stage or character of the work at each particular spindle.

What I claim is:

25 1. In a lens grinding machine, tool-carrying spindles, separate vertically arranged shafts belted thereto, a continuously rotating counter-shaft, separate means for clutching said spindle-driving shafts into driven relation from said counter-shaft, work-supporting devices, means for guiding the same to reciprocate in a rectilinear path across the tool-carrying spindles, and means for reciprocating the same from said spindle driving shafts in a direction at right angles to said first named reciprocation.

2. In a lens grinding machine, a tool-carrying spindle, a work-supporting device, means for reciprocating said device across 40 the end of the tool-carrying spindle, means for adjusting the throw of said work-supporting device, and means for laterally adjusting the line of movement thereof.

3. In a lens grinding machine, a tool-carrying spindle, a shaft for driving the same, means for changing the speed ratio of such driving connection, a source of power, a

work-supporting device, and means connected with said shaft for reciprocating the work-supporting device across the end of the 50 tool-carrying spindle in a rectilinear path.

4. In a lens grinding machine, a spindle, a tool-carrying cross-head adapted to reciprocate across the end of said spindle, connections between said spindle and cross-head for 55 reciprocating the latter, a shaft operatively connected to said spindle for driving the same, a work supporting device adapted to reciprocate in a path across the direction of movement of said cross-head, and connections between said shaft and said device to reciprocate the latter.

5. In a lens grinding machine, a tool-carrying spindle, a driving shaft for said spindle, a work-supporting device guided to 65 reciprocate across the end of said spindle, means connected to said shaft for reciprocating said device, a tool, and means operated by said spindle for reciprocating said tool, across the path of movement of the work- 70 supporting device.

6. In a lens grinding machine, a spindle, a device having a cross head detachably receivable over the end of said spindle, connections between said spindle and cross-head 75 for reciprocating the latter, a work-supporting device movable across the direction of movement of said cross head, and means for driving said spindle and reciprocating said work-supporting device.

7. In a lens grinding machine, a frame having a pan, a spindle projecting into said pan, a device received above said pan and having a cross-head, connections between said spindle and said cross head for reciprocating the latter, a work-supporting device, and means for reciprocating the latter across the direction of movement of said cross-head.

In witness whereof, I subscribe my signature, in the presence of two witnesses.

FERDINAND BUCHHOP.
